UNITED STATES PATENT OFFICE

150,719

DESIGN FOR AN ELECTRIC RANGE

Raymond Loewy, New York, N. Y., assignor to
General Motors Corporation, Dayton, Ohio, a
corporation of Delaware

Application March 21, 1947, Serial No. 137,799

Term of patent 7 years

(Cl. D81—4)

To all whom it may concern:

Be it known that I, Raymond Loewy, a citizen of the United States, residing at New York city, in the county of New York and State of New York, have invented a new, original, and ornamental Design for an Electric Range, of which the following is a specification, reference being had to the accompanying drawing, forming part thereof.

The figure is a perspective view of an electric range, showing my new design. The other side of the range, not shown, is substantially like the side shown.

I claim:

The ornamental design for an electric range, as shown and described.

RAYMOND LOEWY.
